UNITED STATES PATENT OFFICE.

DE WITT C. BOUTON, OF ITHACA, NEW YORK.

DESIGN FOR A DOLL.

SPECIFICATION forming part of Design No. 31,663, dated October 17, 1899.

Application filed September 11, 1899. Serial No. 730,190. Term of patent 7 years.

To all whom it may concern:

Be it known that I, DE WITT C. BOUTON, a citizen of the United States, residing at Ithaca, in the county of Tompkins and State of New York, have invented and produced a new and original Design for Dolls, of which the following is a specification, reference being had to the accompanying drawing, forming a part thereof, and in which I show the body provided at each end with head and arms, the head at one end being intended to be that of a colored person and the head of the other end being intended to be that of a white person.

As shown in the drawing, the leading or material feature of my design consists of a body *a*, having at each end a head *b* and *c*, and intermediate the heads and body and extending in opposite directions are arms *d*.

The head *b* is intended to represent the head of a white and civilized person, while the head *c* is intended to represent the head of a colored or uncivilized person, each head having a suitable facial expression imparted thereto in any suitable manner.

Having described my invention, what I claim, and desire to secure by Letters Patent, is—

The design for a doll, substantially as herein described, and shown.

In witness whereof I have hereunto set my hand this 24th day of August, 1899.

DE WITT C. BOUTON.

Witnesses:
